UNITED STATES PATENT OFFICE

PETER VAN NORDEN, OF OTSEGO, MICHIGAN, ASSIGNOR OF ONE-HALF TO CLEMENT F. SISSON, OF KALAMAZOO, MICHIGAN

PAPER MAKING MACHINE

Application filed December 2, 1932. Serial No. 645,375.

The main objects of this invention are:

First, to provide in a paper making machine a driving means for the forming apron or web by means of which a uniform 5 tension is maintained on the web, thereby avoiding undue stretching which results in variation in the web of paper formed and minimizes wear.

Second, to provide in a paper making 10 machine an improved driving means for coacting rollers whereby variation in diameter of the rolls is compensated for.

Third, to provide an apparatus having 15 these advantages which can be readily installed in standard types of paper making machines, either as an addition or modification thereof or in new equipment.

Objects pertaining to details and economies of my invention will definitely appear 20 from the description to follow. The invention is defined in the claims.

A structure which embodies the features 25 of my invention is clearly illustrated in the accompanying drawings, in which:

Fig. 1 is a fragmentary side elevation of a paper making machine embodying the features of my invention, the machine being largely shown in conventional form.

Fig. 2 is a fragmentary view partially in 30 section on line 2—2 of Figs. 1 and 3.

Fig. 3 is a transverse section on line 3—3 of Fig. 2.

Fig. 4 is a detail view partially in section on line 4—4 of Fig. 2.

Fig. 5 is an enlarged fragmentary elevation 35 showing driving connections for a coacting pair of rollers.

Fig. 6 is a fragmentary side elevation of these rollers.

Fig. 7 is a perspective view of a modified 40 form or embodiment of the structure shown in Figs. 5 and 6.

In the embodiment of my invention illustrated 1 represents the stock feed box and 2 45 the coacting cylinders. The forming web or felt 3 is held in proper relation to the cylinders 2 by means of the rollers 4. The web driving cylinder 5 is disposed at the front end of the machine and is driven through a planetary gearing consisting in

the embodiment illustrated of opposed bevelled gears 6 and 7. The gears 6 are keyed to the journal 8 of the shaft 5 and the gears 7 are journaled to a stub shaft 9 alined with the journal 8. The journal 8 is supported in a bearing 10 while the stub shaft 9 is carried by a pedestal 11.

Planetary gears 12 coacting with the gears 6 and 7 are carried by the pulley 13 driven by the belt 14 connected to the line shaft 15 through the jack shaft 16 and suitable gearing.

The shaft 9 has a brake drum 17 keyed thereto, one end of the flexible brake strip 18 being anchored at 19. The strip is passed over the drum and provided with a hanger 20 for weights 21. There is a plurality of these weights so that the amount of braking friction can be regulated as desired. It will be understood that the speed of the cylinder 5 relative to the pulley is varied according to the braking action on the gear 7. When the whole planetary gearing revolves as a unit the cylinder is driven at the same speed as the pulley, but when the gear 7 is retarded a variation in speed results.

A coacting pair of rollers 22 and 23 are arranged at the opposite end of the forming web and at the rear of the press rolls 24, there being a series of these rolls. One of this pair of rollers as 22 in the embodiment shown in Figs. 5 and 6 is driven from the line shaft 15 by means of the belt 25 coacting with a pulley 26 on the shaft 27 of the roll 22. The shaft 27 is provided with a gear 28 meshing with the gear 29 connected to the shaft 30 of the roll 23 through a one-way roller clutch 31.

In the embodiment shown in Fig. 7 the lower roller 32 is provided with the clutch driving connection 33 to its gear 34, the upper roller 35 being provided with a coacting driving gear 36. It not infrequently happens that one of a coacting pair of rolls is of somewhat less diameter than the other owing to wear or the regrinding of the roller to true it up, and this results in a sliding of the surface of such roller on the forming apron or web or on the web of paper thereon,

tending to displace the fibers or to unduly wear the forming web.

With this arrangement of parts there is a compensating action and by combination of the two driving means described a substantially uniform pull or driving tension may be had on the web which enables production of a web of paper of full width, and the wear on the web is minimized.

I have illustrated parts of the paper making machine mainly in conventional form for convenience in illustration. I have not attempted to illustrate various embodiments and adaptations which I contemplate as it is believed that this disclosure will enable those skilled in the art to embody or adapt my improvements as may be desired.

Having thus described by invention what I claim as new and desire to secure by Letters Patent is:

1. A paper making machine comprising a forming web, a driving cylinder for said web, driving means for said cylinder including a planetary gearing consisting of a pair of opposed gears, one of which is connected to said cylinder and the other of which is provided with a variable friction brake and a pulley having planetary gears coacting with said pairs of gears, a coacting pair of web driving rolls, one of which is provided with a gear and with a driving connection to said pulley, and a coacting gear having a one-way clutch driving connection to the other roll.

2. A paper making machine comprising a forming web, a driving cylinder for said web, driving means for said cylinder including a planetary gearing consisting of a pair of opposed gears, one of which is connected to said cylinder and the other of which is provided with a variable friction brake and a pulley having planetary gears coacting with said pair of gears, a coacting pair of web driving rolls, one of which is provided with a driving connection to said pulley, and a driving connection for such roll to its coacting roll including a one-way clutch.

3. A paper making machine comprising a forming web, a driving cylinder for said web, driving means for said cylinder including a planetary gearing consisting of a pair of opposed gears, one of which is connected to said cylinder and the other of which is provided with a variable friction brake and a pulley having planetary gears coacting with said pair of gears.

4. A paper making machine comprising a forming web, a driving cylinder coacting therewith, driving means for said cylinder comprising a differential gearing, one member of which is provided with a variable friction brake whereby the speed of the cylinder may be controlled, a coacting pair of web driving rollers, one of which is provided with a gear and with a driving connection to said differential, and a coacting gear

having a roller clutch driving connection to the other roll.

5. A paper making machine comprising a forming web, a driving cylinder coacting therewith, driving means for said cylinder comprising a differential gearing, one member of which is provided with a variable friction brake whereby the speed of the cylinder may be controlled, a coacting pair of web driving rollers, one of which is provided with a driving connection to said differential gearing, and a driving connection for such roll to its coacting roll including a one-way clutch.

6. A paper making machine comprising a forming web, a driving cylinder coacting therewith, driving means for said cylinder comprising a differential gearing, one member of which is provided with a variable friction brake whereby the speed of the cylinder may be controlled.

7. A paper making machine comprising an endless web, a driving cylinder therefor, press rolls coacting with said web, a friction-controlled planetary driving gearing for said cylinder, and a coacting pair of driving rolls at the rear of said press rolls, one of said pair of rolls having driving connection to said planetary gearing and the other having a driving connection to such roll including a one-way clutch.

8. A paper making machine comprising a forming web, a pair of coacting rolls, one of which is provided with a gear and with a driving connection, and a coacting gear having a roller clutch driving connection to the other roll.

9. A paper making machine comprising an endless web, press rolls coacting therewith, and a coacting pair of driving rolls at the rear of said press rolls, one of said pair of rollers having a driving connection and the other having a driving connection to such roll including a one-way clutch.

10. A paper making machine comprising a forming web, a pair of coacting rolls, one of which is provided with a driving connection, and a driving connection to the other roll including a one way clutch.

In witness whereof I have hereunto set my hand.

PETER VAN NORDEN.
